HYDROCARBON CONVERSION PROCESS

Joseph W. Jewell, Summit, N.J., assignor to The M. W. Kellogg Company, Jersey City, N.J., a corporation of Delaware

Application December 9, 1953, Serial No. 397,160

17 Claims. (Cl. 208—74)

This invention relates to an improved method of processing residual oils for the production of gasoline, and more particularly, it pertains to the catalytic cracking of residual oils for conversion to a gas oil product which is especially suited as feed stock to a second catalytic cracking treatment in which a gasoline of high anti-knock quality is obtained.

In conventional catalytic cracking operations a residual oil is not charged as the sole feed material for direct production of gasoline, because experience has shown that residual oils, in general, contain an undesirable quantity of metal contaminants which seriously reduce the life of cracking catalysts. Further, residual oils usually contain carbon residue in excess of 0.6% by weight, and this value is recognized at the present time as the limit above which coke production becomes uneconomical for operations involving the direct production of gasoline at conversion levels in the order of about 40 or 45 to about 65. As a result, in the majority of catalytic cracking operations of the type described above, gas oil is the sole feed material or a mixture of gas oil and a limited amount of residual oil is used.

Residual oil is a distress stock in the petroleum industry, because, at present, a satisfactory method of processing this material economically to a valuable product is not known. A substantial amount of the residual oil is sold as fuel oil, which is significantly less profitable than the sale of gasoline. Extensive effort is being made to process residual oil for the production of more valuable products, however, the characteristics of this material present many difficulties for commercial exploitation. As previously indicated, residual oils contain large quantities of components having high coke forming tendencies and also metal in the combined form which exerts adverse effects on the selectivity and activity of cracking catalysts. The processing of these materials in cracking operations at conversion levels of 40 or more has been found not too satisfactory, and the main justification for this operation is the lack of a better treatment for gasoline production. Careful study of this problem led to the conclusion that one of the major reasons for excessive coke formation from residual oils at high conversion rates was the unavoidable difference between the average and maximum time of contact in a catalytic reactor. This led to the further conclusion that if a reactor were designed to minimize this difference, and if the conversion level were lowered to reduce the required average time, that a large yield of gas oil suitable for further catalytic cracking could be produced without excessive coke formation. A small fraction of unreacted oil, if desired, could be rejected as unsuitable for catalytic cracking, and this fraction would contain a high percentage of the carbon residue and metals in the residual feed. Furthermore, any gasoline made in this stage would be a much better quality than could be produced by coking or thermal visbreaking of the residual feed. When residual oil is subjected to catalytic cracking there is a relatively high deposition of coke on the catalyst. At high conversion

rates this quantity is materially increased and since it appears that high coke on catalyst serves to enhance or catalyze further coke production, it follows that the initial gas oil produced from cracking heavy components of the residual oil forms more coke upon further cracking than if gas oil so produced had been charged as the initial feed material to an operation in which coke on catalyst could be kept at a low level. The same theory of operation appears to apply to gas production. Hence, in the operations practiced today, for a given amount of gasoline produced by catalytic cracking of residual oils there may result, a higher yield of coke and normally gaseous product material than the method of the present invention. Further, the cost of catalyst replacement in heretofore methods of processing residual oils may be greater than in the method of this invention.

An object of this invention is to provide an economical and effective method of processing residual oils for ultimate gasoline production.

Another object of this invention is to process residual oils under conditions suitable for the production of feed material for severe catalytic cracking operations to produce high quality gasoline.

Still another object of this invention is to provide a method of catalytically cracking residual oils for the preparation of superior gas oil feed stock for the further production of gasoline by catalytic cracking.

Other objects and advantages of this invention will become apparent from the following description and explanation thereof.

It is contemplated by means of this invention to first subject a residual oil to contact with a cracking catalyst under cracking conditions to produce a gas oil product at a conversion level of about 5 to about 20%, and subjecting the gas oil thus produced to a cracking catalyst under cracking conditions to produce a gasoline product at a conversion level of at least about 35%.

In catalytic cracking operations, the conversion level serves adequately to describe the severity of the operation. The severity desired may be attained by regulating the temperature, the time of contact, the catalyst to oil ratio or the level of catalyst activity. It is the relative effect of these variables with which we are concerned in accomplishing our invention, particularly, the effect of the rate of catalyst circulation and the level of catalyst activity. The best method available for indicating severity at present, is to describe a cracking operation by reference to the conversion level, which is defined by the formula:

$$50 \quad \text{Percent conversion} = 100 \times \frac{V_f - V_p}{V_o}$$

wherein V_f is the volume of feed boiling above 400° F., V_p is the volume of product boiling above 400° F. and V_o is the volume of feed.

55 In the mild treatment of residual oil, in accordance with this invention, the conversion level is maintained not higher than about 20%. The residual oil to be used in this treatment may or may not contain gas oil components which can be satisfactorily processed in the severe

60 cracking operations. If the feed does contain such gas oil components the operating conditions will be such as to minimize conversion of such gas oil. It is preferred that the residual oil contain substantially all of the metal contaminants and carbon residue of the crude oil, and that any material which can be separated therefrom, substantially free of metal contaminants and carbon residue

65 should not be included as part of the residual oil feed to the mild cracking step. Hence, the mild cracking step is of such severity that substantially all of the metal contaminants and carbon residue are deposited on the catalyst, and the principal product is a gas oil substantially free of metal contaminants and carbon residue. In in-

stances where metal contamination of residual oil is extremely high, it may be desirable to discard a portion of the liquid product boiling higher than gas oil from the mild cracking operation in order to avoid an unduly high rate of catalyst deactivation. The primary cracking reactions in the mild treatment involve essentially the cracking of components in the residual oil boiling range to products in the gas oil boiling range with consequent deposition of metal contaminants and carbon on the catalyst and the production of a gas oil suitable as feed for severe cracking to gasoline, and with the practical minimum production of gasoline. It should be recognized that any gasoline so produced will be much superior to gasoline produced in a thermal vis-breaking operation.

The mild cracking operation is conducted at a temperature of about 700° F. to about 1000° F., more usually, about 800° to about 900° F. The pressure used can be at atmospheric level or it can be as high as 50 p.s.i.g. Higher superatmospheric pressures are avoided only to the extent required by the problem of the degree of vaporization necessary to distribute the feed on the flowing catalyst. Within the scope of the present invention, this problem can be substantially eliminated within economic limits by injecting gaseous materials into the cracking zone for the purpose of decreasing the partial pressure of the residual feed, and so promote its vaporization. For this purpose, steam can be used, which can be produced by utilizing the heat of combustion in the regeneration zone of the system. Another gaseous material which can be used is hydrogen, and it can also serve to suppress the adverse effects of metal contaminants on catalyst life and/or to reduce carbon or coke formation. The normally gaseous hydrocarbon product from severe gas oil cracking which contains hydrogen in admixture with C₁-C₃ paraffins or olefins, can be used. In some instances, the flue gas from the regeneration zone might be used for this purpose.

The quantity of residual oil processed relative to the amount of catalyst contacted therewith is measured in terms of the weight space velocity, which is defined as the pounds of oil feed charged to the reaction zone on an hourly basis per pound of catalyst present therein. The weight space velocity can vary over a wide range, namely about 0.1 to about 15, however, more usually, it will be about 1 to about 10. In either a fluid bed or a moving bed system, the catalyst to oil ratio is measured as the rate of catalyst being circulated to the oil feed rate, on a weight basis. Generally, for the mild cracking operation, the catalyst to oil ratio can vary from about 0.1 to 20, more usually, about 0.5 to 5.0. Further, the residual oil feed can be preheated under suitable conditions, which may include mild thermal cracking, in order to reduce the catalyst-oil ratio required for satisfactory adsorption of the feed on the catalyst.

The catalyst employed for the mild cracking operation can be any suitable cracking catalyst such as, for example, a silica containing cracking catalyst or a siliceous catalyst commonly used for this purpose in known cracking operations. The silica containing cracking catalyst can have about 10 to about 100% silica, based on the total weight of the catalyst, although more usually, silica comprises the majority but not all of the catalytic material, for example, in amounts of about 15 to about 95% by weight of the total catalyst. Specific examples of cracking catalyst which can be used for the purposes of mild cracking in the present invention are bauxite, silica gel, Superfiltrol, various types of clays, silica-alumina, silica-magnesia, silica-zirconia, silica-boria or mixtures of the foregoing. The synthetically prepared silica containing gel catalysts such as, for example, silica-alumina, silica-magnesia, etc., in which silica comprises about 70 to about 90% by weight of the total catalyst, are specially suited for the mild cracking operation. The cracking catalyst described above is prepared by various methods well-known in the art. Therefore, it is not necessary to

furnish a description herein. When hydrogen is used as a diluent gas, it may be desirable to incorporate a hydrogenating component in the cracking catalyst. Suitable hydrogenation components for this purpose are metals of group VIII, compounds of the left-hand elements of groups V and VI, etc. More particularly, the hydrogenating component may be nickel, cobalt, iron, platinum and palladium and/or the oxides and/or sulfides thereof; the oxides and/or sulfides of molybdenum, chromium, vanadium and tungsten, etc. Specific examples of these hydrogenating components are molybdenum trioxide, chromium oxide, tungsten oxide, tungsten sulfide, nickel oxide, cobalt oxide, etc. When a hydrogenating component is used in combination with the cracking catalyst, generally, it constitutes 0.1 to about 15%, based on the total weight of the catalyst. The activity of the cracking catalyst is based on a D+L activity rating which is described in an article by R. V. Shankland and G. E. Schmitkons published in Ind. Eng. Chem., vol. 39, 1947, page 1138, and in the report of the 27th annual meeting of the American Petroleum Institute, November 1947.

In the mild cracking operation, the catalyst due to metal contamination becomes permanently deactivated and, hence, requires replacement at such a rate as to maintain a desirable D+L activity. Generally, for this purpose, the average activity of the catalyst in the mild cracking zone is maintained at about 10 to about 25 D+L. The catalyst replacement to maintain this activity is preferably effected by using, as makeup, catalyst which is withdrawn from the severe cracking zone. In the severe cracking zone the average activity is maintained at about 20 to about 45 D+L. In the preferred operation, freshly prepared or new cracking catalyst having an activity of about 40 to about 70 D+L is charged to the severe cracking operation in an amount sufficient to provide catalyst replacement for both mild and severe cracking operations. It is preferred to use catalyst having a lower D+L activity than fresh catalyst in the mild cracking operation, because there is a tendency for over-cracking to occur when highly active catalyst comes into contact with a residual oil stock. A high catalyst replacement rate for the mild cracking operation will result in the maintenance of a higher average D+L activity in a severe cracking operation than is considered economical in a conventional system. For the purposes of this invention, it is preferred to maintain an average D+L activity of about 30 to about 36 in the severe cracking zone. In conventional operations, it is customary to maintain an average D+L activity of about 23 to 26 for the production of gasoline. The maintenance of a higher activity level for the severe cracking operation results in several advantages. In one instance, a better product distribution may be obtained by the use of a higher activity level. In another case where a given product distribution is desired, the higher activity level can be used to reduce the required reaction temperature. Such reduction of temperature will require less heat from the regenerator and thus reduce the C/O ratio, which in turn improves product distribution, or to reduce the regenerator temperature which improves catalyst life. For a given performance, another method of compensating for the increase in activity level is to reduce the quantity of catalyst in the reaction zone and, hence, a smaller size reaction vessel can be used, and a consequent higher space velocity.

When the average D+L activity of catalyst in the severe cracking operation is maintained at about 30 to about 36, it is preferred to maintain an average D+L catalyst activity in the mild cracking zone of about 10 to about 20. In essence, the circulation of catalyst in the entire system from the standpoint of replacement involves withdrawing catalyst from the mild cracking zone to discard the same from the system at a rate sufficient to maintain the desired activity level therein. The loss of inventory in the mild cracking zone is made up by

utilizing catalyst which is withdrawn from the severe cracking operation, and in turn, the catalyst inventory in the severe cracking zone is maintained by charging thereto fresh or new catalyst at the same rate. It is preferred that the catalyst used as replacement for the mild cracking operation is withdrawn from the regeneration system of the severe cracking operation.

As mentioned above, the catalyst in the mild cracking operation becomes contaminated with metals and these metals are undesirable in their effect because they shorten the life of the catalyst and can have an adverse effect upon product distribution. In order to offset at least in part this undesirable effect of metal contamination, it is contemplated using all the product vapor from severe cracking or at least that portion which is normally a dry gas product. This gas containing a considerable portion of hydrogen in admixture with C₁–C₃ hydrocarbons can be used in place of steam to reduce the partial pressure of the oil feed. With less steam the overall deactivation of catalyst may be reduced. The high partial pressure of excess hydrogen and light hydrocarbons may also serve to suppress carbon formation.

As a result of the mild cracking operation, carbonaceous material is deposited on the cracking catalyst and in order to restore the temporary reactivating effects of this deposit, the catalyst may be subjected to a regeneration treatment by means of an oxygen containing gas such as, for example, air, diluted air containing about 2 to about 15% by volume of oxygen, etc., and at a temperature in the order of about 800° to about 1250° F., more usually, about 950° to about 1050° F. The cracking operation is endothermic in nature, consequently, heat must be supplied in order to maintain the desired temperature. It is known that a substantial amount of the heat can be supplied by circulating catalyst at a sufficient rate such that the sensible heat above reactor temperature level contained in the catalyst can be utilized for furnishing the required endothermic heat of reaction in the cracking zone. This principle can be used in the present invention in order to attain what is commonly referred to as a heat balance system. However, it is also contemplated preheating the feed, using lower catalyst to oil ratios in the order of about 1 to about 5 and utilizing the heat of combustion in the regeneration zone for the purpose of generating steam. As a result of producing a minimum yield of gasoline product in the mild cracking operation and selecting conditions so as to selectively crack compounds boiling in the residual oil range to gas oil components, the endothermic heat requirement of the reaction is significantly less than is normally required for a conventional cracking operation. In view thereof, by using the preheating step for the residual oil feed to the cracking operation, a lower catalyst to oil ratio can be used effectively to improve product distribution as well as to reduce any loss of product materials being burned in the regenerator. Further the heat of combustion can be used for heating a diluent gas such as, for example, hydrogen containing gas, normally gaseous hydrocarbons, etc., and the heated gaseous materials can be fed to the mild cracking zone for the dual purpose of reducing the partial pressure of the residual oil and supplying at least part of the endothermic heat of reaction.

Except for the increased level of catalyst activity the severe cracking step of this invention is operated in the same manner as is commonly practiced in the art today. In this type of an operation, the feed material consists primarily of a gas oil having an initial boiling point in the order of about 350° to about 450° F. and an end point of about 850° to about 1000° F. or higher. The feed material can consist entirely of the gas oil which is produced from the mild cracking operation, or it can be a mixture of the gas oil product from the mild cracking step and a straight run gas oil. As a result of the economic limits of conversion in the severe cracking operation the product contains a gas oil fraction and this is

ordinarily referred to as cycle oil. This product material may or may not be recycled to the severe cracking zone, and if not so used, it is withdrawn for use outside the unit. This operation is similar to the type which is in practice at the present time in some commercial operations. For the purpose of this invention, the severe operation is designed to produce primarily a gasoline product. The severity, in terms of conversion level, is at least about 35% up to about 70%, although, more usually, it is about 45 to about 65%. The operating conditions which are used in this part of the process fall essentially within the same range as described hereinabove for the mild cracking step, however, the conditions are selected on the basis of selecting those variables whose combined effect is severe in nature. The method of effecting a severe operation is well-known to those skilled in the art, hence, it is not necessary to furnish details herein. In general, the temperature for the severe cracking step is about 800° to about 1050° F., more usually, about 900° to about 1000° F. The pressure under which this reaction is effected can be at an atmospheric level or up to about 50 p.s.i.g. Usually, the lower pressure levels are preferred such as, for example, 10 to about 20 p.s.i.g. The weight space velocity as defined hereinabove varies from about 0.1 to about 10, more usually, about 0.5 to about 5. In the severe cracking operation, the catalyst to oil ratio can be varied considerably over a wide range of about 0.5 to about 25, however, more usually, a catalyst to oil ratio of about 2 to about 10 is used.

The catalyst to be used in the severe cracking step can be any one or more of those described hereinabove in connection with the mild cracking operation. In commercial practice, however, the most widely used catalysts are either Superfiltrol or synthetic silica-alumina catalyst. Superfiltrol is an acid treated Bentonite clay which is referred to as a natural catalyst; whereas the synthetic silica-alumina is prepared by methods well known to those skilled in the art from various chemical compounds as starting materials. In some commercial operations, mixtures of silica-magnesia and silica-alumina have been used in order to obtain improved selectivity or higher liquid production. However, silica-magnesia results in a lower octane product, consequently, its use depends upon the result desired for this type of operation. It was noted hereinabove in connection with the catalyst to be used in the mild cracking step that the discarded catalyst from the severe cracking zone can be used for the mild cracking operation. This technique has its obvious economical advantages, however, in mild cracking operations where large quantities of steam are employed for the purposes indicated above, it may be desirable to employ Superfiltrol as the fresh cracking catalyst rather than synthetic silica-alumina by reason of its greater stability towards steam. Where steam stability is important, the effect can also be had by using silica-magnesia or a mixture of silica-magnesia and silica-alumina in the severe cracking operation and supplying the discarded catalyst to the mild cracking operation. Silica-magnesia has a significantly greater stability towards steam than silica-alumina. Consequently, it would be expected that the activity of the catalyst in the mild cracking zone would decline less rapidly.

The residual oil to be processed in the present invention can be a reduced crude which constitutes about 20 to about 50% of the total crude and has an API gravity of about 10 to about 25. Reduced crudes can be readily used in fluid catalytic cracking systems without taking extreme measures to insure complete vaporization of the feed material to avoid defluidization of the reaction bed through wetting of catalyst particles. Generally, these reduced crudes contain about 30 to about 90% of components boiling above 700° F. Those materials which boil above 700° F. are relatively easily cracked to coke and normally vaporized products and, hence, the quantity of these materials in a feed stock can serve to indicate

qualitatively the "crackability" or susceptibility to cracking of such materials. There are also present in reduced crudes compounds of a highly asphaltic nature, sulfur containing compounds and salts of metals which have an adverse effect upon cracking catalyst activity. In general, the carbon residue of a reduced crude is at least 1% by weight, more usually, about 2.5 to about 30% by weight. The sulfur content may vary widely depending upon the source from which the crude oil is obtained. In general, the sulfur content of reduced crude is at least 0.1% by weight, more usually, about .2 to about 10% by weight. The metal contaminants in the reduced crude are measured in terms of a so-called "nickel equivalent" in parts per million, p.p.m., and this serves to indicate the total concentration of metal contaminants on an equivalent nickel basis. The metals normally found in reduced crudes and which cause adverse effects on cracking catalyst activity are, for example, nickel, copper, iron, vanadium and cobalt. Since nickel causes the greatest amount of deactivation of the metal contaminants, the nickel equivalent basis has been used to designate the combined effect of the concentration of these contaminants. Generally, in reduced crudes, the nickel equivalent may be at least about 0.5 p.p.m., and when the metal contaminants constitute at least 2 p.p.m. on a nickel equivalent basis, there is a significant effect upon cracking catalyst activity. It is found, however, that a large number of reduced crudes contain about 5 to about 70 p.p.m. of metal contaminants on the nickel equivalent basis. The preferred feed stocks for the mild cracking operation contain essentially all of the metal contaminants of the crude oil and a quantity of the carbon residue such that the gas oil employed as feed stock for the severe cracking operation contains not more than about 0.4 to 0.8% carbon residue. When the gas oil is the sole feed to the severe cracking operation the carbon residue does not exceed about 0.6%. The heavy residual oils can be used as feed to the mild cracking operation. The heavier residual oils are, for example, vacuum tars, residual tars, fuel oils, etc., which have API gravities in the range of about 1 to about 12. These stocks present difficulties in fluid systems by reason of the high boiling nature of the compounds making up the material. A large part or all of such heavy residual oils are liquid at the temperatures used in the mild cracking operation. The ease with which the compounds in these heavy residual oils are cracked, is an important factor in establishing conditions for the operation in which they are used. Since these stocks are cracked easily and they are of a high boiling nature, care is taken in determining the quantity of catalyst for contact therewith at the point of charging the liquid feed to the reaction zone with large quantities of diluent gas, e.g., steam, in order to reduce the partial pressure of the oil and thus to increase the degree of vaporization and the ease of distribution thereof on the catalyst surface.

The metal concentration, sulfur and carbon residue of these heavy residual oils is on the average higher than reduced crudes, although the amounts will fall within the ranges specified hereinabove for the reduced crudes. With respect to the boiling characteristics of the heavy residual oils, for the purposes of this specification and the appended claims, such materials have an initial boiling point of about 850° to about 1000° F. Since the heavy residual oil comprises the heaviest fraction of the total crude, it is not necessary to specify the end point by reason that the boiling point of the heaviest compound in total crude will be representative of the end point of the heavy residual oil. It should be understood that the term "residual oil" as used for this specification and the appended claims, includes reduced crude and heavy residual oils.

The separation of suitable feed material, from the reduced crude for the severe cracking operation can be accomplished by distillation under vacuum or other suit-

able separation means. In one embodiment, crude oil is topped or separated by suitable means, e.g., distillation, to separate therefrom straight run gas oil. The straight run gas oil is charged to the severe cracking operation. The reduced crude from the topping operation may be further subjected to distillation under vacuum to separate a gas oil fraction which is suitable for severe cracking and a residual oil fraction. The gas oil fraction from the vacuum distillation operation is charged to the severe cracking operation. The residual oil fraction is charged to the mild cracking zone, and a gas oil product is obtained which is charged to the severe cracking operation. In one aspect of this invention the reaction product from the mild cracking zone can be passed to the crude oil topping unit for separation of the gas oil product with the straight run gas oil. The total feed to the severe cracking operation should have less than about 2 p.p.m. of metals, nickel equivalent, preferably less than about 1 p.p.m. of metals, nickel equivalent.

The catalyst particles for the fluid system of this invention will have a size ranging from about 0 to about 250 microns, more usually, about 10 to about 100 microns. The gaseous materials being passed upwardly in the reaction, regeneration and stripping zones, will have a superficial linear gas velocity in the range of about 0.1 to about 50 feet per second. For commercial practices, the superficial linear gas velocity of the upflowing materials is usually about 1 to about 2.5 feet per second in the processing zones of a bottom drawoff phase system. It is also contemplated involving an upflow type of system in which the superficial linear gas velocity is sufficient to carry overhead all of the finely divided catalytic material which is introduced into the processing zone. In the upflow system, the superficial linear gas velocities in the processing zones are about 2 to about 10 feet per second. The use of heavy residual oil as feed material to the mild cracking zone may advantageously employ the upflow technique in order to avoid defluidization effects. The upflow system is referred to, generally, as the high velocity method, and it has the advantage of providing a more uniform residence or contact time between the catalyst particles and the gaseous material.

In order to provide a better understanding of the present invention, reference will be had to the accompanying drawing which forms a part of this specification.

In the figure, reduced crude containing a fraction of clean gas oil is heated to a suitable temperature and is charged from line 100 to the lower part of fractionating tower 101. In fractionating tower 101, the portion of reduced crude which consists of gas oil substantially free of metals and carbon residue is yielded overhead through a line 102; whereas the heavy residual oil is separated and yielded as a bottom fraction through a line 103.

The gas oil which is separated from the reduced crude in tower 101 is combined with heavy recycle gas oil which is supplied by means of line 190, and with light recycle gas oil which is supplied by line 192. The heavy and light recycle gas oil streams are withdrawn from tower 113 as side stream products and they are divided such that part of each stream may be passed to storage for further treatment and the remaining part is combined with the virgin gas oil from line 102. It should be noted that the heavy and light gas oil side streams from fractionator 113 are composed partly of refractory cycle gas oil from severe gas oil cracking and partly of product gas oil from the mild cracking step. The gas oil produced overhead from tower 101 is combined with the light and heavy gas oil fractions from fractionator 113 and the total material is charged to a furnace 200 wherein it preheated to a temperature of 600°-900° F. The preheated feed material is discharged from furnace 200 by means of a line 202, and thence, it is fed into a transfer line 204 wherein it picks up regenerated catalyst

flowing from standpipe 206, containing a slide valve 208, and transporting the same to an upflow reactor 210. Steam may be injected in line 202 through line 260, if desired. In the upflow reactor, the temperature is maintained at about 900°-950° F., at a total pressure of 15-16 p.s.i.g., the catalyst to oil ratio is from 3 to 10:1, and the quantity of catalyst which is present in the reactor 210 relative to the oil feed provides a space velocity of 0.5-5 V_o/hr./V_c. Under the conditions existing in this reactor, 55-65% of conversion is effected. The superficial linear gas velocity of the reactant materials is 2.6-6.0 feet per second, and it is sufficient to carry overhead from the reactor 210 all of the catalytic material being supplied through transfer line 204. The vaporous reaction product and spent catalyst are removed from the reactor 210 by means of a line 212, and it is transferred to the upper part of a reactor hopper 214. A spent catalyst bed E is situated in reactor hopper 214, and it has a level 216. Stripping steam is introduced from line 218 to the bottom part of reactor hopper 214 at the rate of 1 to 5 volumes of steam per volume of fluidized catalyst being circulated. Bed E in reactor hopper 214 is maintained in a dense phase, and at a temperature of about 900°-1050° F. The vaporous reaction product is removed from reactor hopper 214, and it flows into line 121, wherein it is mixed with the tar fraction of the reduced crude for processing in reactor 126. Spent catalyst is withdrawn from reactor hopper 214 by means of standpipe 220, in which there is installed a slide valve 222. Air is supplied from a main source 224, and it passes through line 226, which serves to pick up catalyst flowing from standpipe 220, and transport the same through transfer line 228 to the upper part of regenerator 230. Flue gas is withdrawn from regenerator 230 by means of a line 232, and any catalyst which is entrained therewith is separated and recovered by means of cyclones, etc., not shown. In the bottom part of regenerator 230, there is situated a grid plate 234, upon which regenerated catalyst bed F is supported. Air is supplied for the purpose of regeneration through line 236 and it passes upwardly through the regenerator by means of line 238. Regeneration of catalyst is effected at a temperature of about 1050° F. and at a total pressure of about 15 p.s.i.g. The spent catalyst contains a carbonaceous content of 1.5-2.5% by weight and by means of regeneration in vessel 230, the carbonaceous content is reduced to about 0.5% by weight. The temperature of regeneration is controlled by withdrawing regenerated catalyst from bed F by means of a standpipe 242, containing a slide valve 244, and transferring the same by means of air which is supplied through line 246 and by means of branch line 248. The regenerated catalyst suspended in air is passed from line 248 through a catalyst cooler 250 wherein the temperature is reduced to about 850° F., and it is returned to the regenerator below grid plate 234 by means of line 254.

The tar fraction from tower 101 is charged to a furnace 105, wherein the temperature of the tar is raised to about 800° F. The preheated tar fraction is discharged from furnace 105 through a line 107, and thence it flows into line 109 in which there is flowing a heavy oil consisting of slurry withdrawn from the bottom of fractionator 113, by means of line 111, and containing catalyst fines commingled therewith and, optionally, other heavy gas oil which is unsuitable for severe cracking and which may be withdrawn from fractionator 113 through lines 138 and 140. The purpose of recycling all or a part of this additional gas oil through the mild cracking zone is to improve its quality as to metal content and/or carbon residue, thus to make it suitable for the severe cracking operation.

The liquid feed material in line 109 is combined with all or part of the reaction product from a severe catalytic cracking operation which is supplied from a line 121.

The vaporous reaction product and liquid feed material are passed as a combined stream in a line 120. Freshly regenerated catalyst from regenerator 164 is supplied from a standpipe 123, containing a slide valve 124, and it flows into line 120 for admixture with the feed material. The mixing of vaporous reaction product with liquid feed serves to vaporize a substantial part of the liquid feed, so that upon mixing with catalyst, uniform absorption of oil on the catalyst is accomplished. The total feed material and regenerated catalyst flows from transfer line 120 into an upflow reactor 126. In reactor 126, the temperature is maintained at about 825° F. and at a total pressure of 12 p.s.i.g. The rate of catalyst being charged to reactor 126 relative to the rate of oil feed on a weight basis, is about 3 to 1. The superficial linear velocity of the reactant materials passing upwardly through reactor 126 is about 3-4 feet per second, and it provides a fluid density of 8-10 pounds per cubic foot. The quantity of catalyst which is present in reactor 126 relative to the oil rate provides a space velocity of 1-10 V_o/hr./V_c. As a result of the conditions existing in reactor 126, 3-10% conversion of feed is effected therein. Catalyst and the product resulting in reactor 126 are withdrawn overhead through a line 127 and discharged to a reactor hopper 129. A fluid catalyst bed C is maintained in reactor hopper 129, and it has a level 130. In reactor hopper 129, any heavy oil which is adsorbed on the catalyst is provided additional residence time for cracking, and a continuous stream of fluidizing gas, e.g., steam, is admitted through line 131 which also serves to strip such heavy oil and cracked product from the catalyst. The vaporous reaction product from the mild cracking operation in reactor 126 is withdrawn overhead from hopper 129 by line 132, and this line, in turn, is connected to the bottom part of fractionating tower 113. In the fractionating tower, the total vaporous feed is separated into various fractions and withdrawn as (a) gasoline and lighter product materials through an overhead line 134; (b) as a light gas oil product which is withdrawn through a line 136; (c) as a heavy oil fraction which is withdrawn from line 138; and (d) as a decanted oil which is withdrawn through a line 140. The withdrawal of these product fractions is facilitated by appropriate means such as tray 142 for the withdrawal of light gas oil, tray 144 for the withdrawal of heavy gas oil and well 146 for the withdrawal of decanted oil. Spent catalyst in reactor hopper 129 is withdrawn therefrom by means of a standpipe 150 in which there is located a slide valve 152. Air which is supplied from a source 154 flows through line 156 and steam or other inert gas is admitted through line 151, and the combined stream serves to carry the spent catalyst in transfer line 158 to regenerator 160. In line 158 and regenerator 160, the entrained light hydrocarbon content of the catalyst is burned plus a part of the coke, under conditions of relatively high velocity. The superficial linear gas velocity of the regenerator gas passing upwardly through regenerator 160 is about 3-4 feet per second, hence, all of the catalyst is carried overhead from the regenerator through a line 162, in which it flows downwardly into the upper part of a regenerator-hopper 164. The downwardly directed inlet helps to reduce the quantity of powder entrained in the gas flow to the cyclone recovery. A regenerated catalyst bed D is maintained in hopper 164, and it has a level 166. Flue gas is removed overhead from the regenerator through a line 168 and any entrained catalyst fines are separated and recovered by means of a cyclone or other suitable recovery means, not shown. The regenerated catalyst bed D is supported on a grid plate 170. Below the grid plate additional combustion air is introduced by means of line 172 at the rate required in order to maintain a fluid bed and to effect the desired regeneration of catalyst. Another portion of regeneration air is passed through a line 174,

and this air stream serves to pick up regenerated catalyst passing downwardly through standpipe 176, containing slide valve 178, and transporting the same through a transfer line 180 for passage through a catalyst recycle cooler 182. The catalyst withdrawn from the regenerator hopper 164 is at a temperature of about 1050° F., and by means of cooler 182, the catalyst temperature is reduced to about 850° F. and it is recycled at the rate required to maintain the regenerator temperature at 1050° F. The combustion air being supplied to lines 10 172 and 174 is supplied by means of line 186.

With respect to catalyst replacement, the operation described above is supplied with fresh catalyst from a storage drum (not shown) to regenerator 230 of the severe cracking operation by means of line 231. Another storage drum (not shown) serves as an intermediate storage vessel for the withdrawal of regenerated catalyst from regenerator 230 for supply to regenerator 164 of the mild cracking operation. Catalyst is withdrawn from the regenerator 164 and discarded from the system to maintain the desired activity level in the mild cracking operation.

Various alternative schemes can be suggested for the above operation. In one instance, the overhead product from reactor hopper 214 can be passed first to a fractionator wherein the gasoline is separated therefrom, and this gasoline fraction alone is charged to line 120 for processing with the heavy residual oil. In another scheme, the heavy residual oil alone is combined with steam and charged directly to the mild cracking reactor 126. The heavy oil discharged from lines 111 and 140 can be recycled to the reactor 126, or these materials can be discarded from the system.

Having thus provided a description of my invention including specific examples, it is to be understood that no undue limitations or restrictions are to be imposed by reason thereof, but that the scope of the present invention is defined by the appended claims.

I claim:

1. A process for the production of gasoline which comprises contacting a residual oil containing at least about 1 percent by weight of carbon residue and substantially free of separable gas oil suitable for high level conversion to gasoline with a diluent to vaporize a substantial portion of said residual oil prior to contact with a cracking catalyst under fluidized cracking conditions to effect during said cracking not more than about 20 percent conversion to a reaction product containing gas oil, separating the gas oil from the reaction product and contacting the same with a cracking catalyst under cracking conditions to effect a conversion of at least about 35 percent for the production of gasoline, said separated gas oil containing not more than about 0.6 percent carbon residue.

2. A process for the production of gasoline which comprises contacting a residual oil containing at least about 1 percent by weight of carbon residue and substantially free of separable gas oil suitable for high level conversion to gasoline with a diluent to vaporize a substantial portion of said residual oil prior to contact with a cracking catalyst under fluidized cracking conditions in a first reaction zone to effect during cracking not more than about 20 percent conversion to a reaction product containing gas oil, separating the gas oil containing not more than about 0.6 percent carbon residue from the reaction product, contacting the separated gas oil with a cracking catalyst under cracking conditions in a second reaction zone to effect a conversion of at least about 35 percent for the production of gasoline and passing a portion of the catalyst from the second reaction zone to the first reaction zone.

3. A process for the production of gasoline which comprises contacting a residual oil containing at least about 1 percent of carbon residue and at least about 0.5 p.p.m. of metals, nickel equivalent and substantially

free of separable gas oil suitable for high level conversion to gasoline with a diluent to vaporize a substantial part of said residual oil prior to contact with a silicious catalyst under fluidized cracking conditions including a temperature of about 800° F. to about 900° F. to effect a conversion of about 5 to about 20 percent to produce a reaction product containing gas oil substantially free of carbon residue and metal contaminants, separating the gas oil from the reaction product and contacting the separated gas oil with a silicious catalyst under fluidized cracking conditions including a temperature of about 800° F. to about 1050° F. to effect a conversion of about 35 to about 70 percent for the production of a high anti-knock quality gasoline.

15 4. A process for the production of gasoline which comprises contacting a residual oil containing at least about 1 percent by weight of carbon residue, at least about 0.5 p.p.m. of metals, nickel equivalent, and substantially free of separable gas oil suitable for high level conversion to gasoline with a diluent to vaporize a substantial portion of said residual oil prior to contact with a fluidized mass of finely divided silicious catalyst having an average *D+L* activity of about 10 to about 25 in a first cracking zone under suitable cracking conditions including a temperature of about 700° F. to about 1000° F. to effect a conversion of about 5 to about 20 percent such that a reaction product containing gas oil substantially free of metal contaminants and carbon residue is obtained, separating the gas oil from the reaction product, contacting the separated gas oil with a fluidized mass of finely divided siliceous catalyst having an average *D+L* activity of about 20 to about 45, said activity being substantially greater than the activity maintained in the first cracking zone, under suitable fluidized cracking conditions including a temperature of about 800° to about 1050° F. to effect a conversion of about 35 to about 70 percent for the production of a high anti-knock quality gasoline, and passing a portion of the catalyst from the second cracking zone to the first cracking zone in a quantity sufficient to maintain the desired *D+L* activity level therein.

40 5. A process for the production of gasoline which comprises contacting a residual oil containing at least about 1 percent by weight of carbon residue, at least about 0.5 p.p.m. of metals, nickel equivalent, and substantially free of separable gas oil suitable for high level conversion to gasoline with a diluent to vaporize a substantial portion of said residual oil prior to contact with a fluidized mass of finely divided siliceous catalyst having an average *D+L* activity of about 10 to about 20 in a first cracking zone under suitable cracking conditions to effect a conversion of about 5 to about 20 percent such that a reaction product containing a gas oil substantially free of carbon residue and metal contaminants is obtained, separating the gas oil from the reaction product, contacting the separated gas oil with a fluidized mass of finely divided siliceous catalyst having an average *D+L* activity of about 30 to about 36 in a second cracking zone under suitable cracking conditions to effect a conversion of about 35 to about 70 percent for the production of a high anti-knock quality gasoline product, and passing a portion of the catalyst utilized for cracking in the second cracking zone to the first cracking zone in a quantity sufficient to maintain the desired *D+L* activity therein.

45 6. A process for the production of gasoline which comprises contacting a residual oil containing at least about 1 percent of carbon residue, at least about 0.5 p.p.m. of metals, nickel equivalent, and substantially free of separable gas oil suitable for high level conversion to gasoline with a diluent to vaporize a substantial portion of said residual oil prior to contact with a siliceous catalyst having an average *D+L* activity of about 10 to about 25 under fluidized conditions at a temperature of about 700° to about 1000° F., at a weight space velocity of about 0.1 to about 15, a catalyst to oil ratio of about 0.1 to about 20, a pressure of about 1 atmosphere to about 50

p.s.i.g., said operating conditions being selected to effect a conversion of about 5 to about 20 percent in order to produce a reaction product containing gas oil substantially free of carbon residue and metal contaminants, separating the gas oil from the reaction product, contacting the separated gas oil with a siliceous catalyst having a $D+L$ activity of about 20 to about 45, at a temperature of about 800° to about 1025° F., a weight space velocity of about 0.1 to about 10, a catalyst to oil ratio of about 0.5 to about 25, a pressure of about 1 atmosphere to about 50 p.s.i.g., and said conditions being selected to effect a conversion of about 35 to about 70 percent to produce a gasoline product of high anti-knock quality.

7. A process for the production of gasoline which comprises contacting a residual oil containing a carbon residue of about 2.5 to about 30 percent, at least about 2 p.p.m. of metals, nickel equivalent, and substantially free of separable gas oil suitable for high level conversion to gasoline with a diluent to vaporize a substantial portion of said residual oil prior to contact with a siliceous catalyst having an average $D+L$ activity of about 20 to about 20 under fluidized conditions at a temperature of about 800° to about 900° F., a weight space velocity of about 1 to about 10, a catalyst to oil ratio of about 0.5 to about 5.0, a pressure of about 1 atmosphere to about 15 p.s.i.g., said conditions being selected to effect a conversion of about 5 to about 20 percent such that a reaction product containing gas oil substantially free of carbon residue and metal contaminants is obtained, separating the gas oil from the reaction product, contacting the separated gas oil with a fluidized siliceous catalyst having an average $D+L$ activity of about 30 to about 36, at a temperature of about 900° to about 1000° F., a pressure of about 1 atmosphere to about 15 p.s.i.g., a catalyst to oil ratio of about 2 to about 10, and said conditions being selected to effect a conversion of about 45 to about 60 percent such that a gasoline product of high anti-knock quality is produced.

8. A process for the production of gasoline which comprises subjecting a crude oil to treatment in a separation zone for the production of a first gas oil fraction and a reduced crude fraction containing about 2.5 to about 30 percent of carbon residue and at least 2 p.p.m. of metals, nickel equivalent, contacting the reduced crude with a hydrocarbon diluent to vaporize a substantial portion of said reduced crude fraction prior to contact with a siliceous catalyst in a first cracking zone under fluidized conditions suitable to effect a conversion of about 5 to about 20 percent such that a reaction product containing gas oil substantially free of carbon residue and metal contaminants is produced, passing the reaction product to the aforesaid separation zone wherein the gas oil product is separated and combined with the first gas oil fraction and the product boiling higher than gas oil is combined with the reduced crude for recycle to the first cracking zone, contacting the total gas oil material with a siliceous catalyst in a second cracking zone under conditions suitable to effect a conversion of about 35 to about 70 percent such that a gasoline product of high anti-knock quality is produced.

9. A process for the production of gasoline which comprises contacting a residual oil containing about 2.5 to about 30 percent of carbon residue, at least 2 p.p.m. of metals, nickel equivalent, and substantially free of separable gas oil suitable for high level conversion to gasoline with a hydrocarbon diluent to vaporize a substantial portion of said residual oil prior to contact with a siliceous catalyst having an average $D+L$ activity of about 10 to about 25 in a first cracking zone under suitable cracking conditions to effect a conversion of about 5 to about 20 percent such that a reaction product containing gas oil substantially free of carbon residue and metal contaminants is produced, separating the gas oil from the reaction product, contacting the separated gas oil with a siliceous catalyst having an average $D+L$ activity of about

20 to about 45 and which is greater than the activity of the catalyst in the first cracking zone under suitable fluidized cracking conditions in the second cracking zone to effect a conversion of about 35 to about 70 percent such that the catalyst becomes contaminated with carbonaceous material and a gasoline product of high anti-knock quality is produced, passing a portion of contaminated catalyst from the second cracking zone to a regeneration zone wherein the catalyst is regenerated by combustion with an oxygen containing gas, passing a portion of regenerated catalyst to the first cracking zone and withdrawing catalyst in a similar quantity therefrom in order to maintain the desired activity therein.

10. A process for the production of gasoline which comprises subjecting a crude oil to treatment in a separation zone for the production of a first gas oil fraction and a reduced crude fraction, subjecting the reduced crude fraction to distillation under vacuum to produce a second gas oil fraction and a residual oil containing about 2.5 to about 30 percent by weight of carbon residue and about 5 to about 70 p.p.m. of metals, nickel equivalent, contacting the residual oil with a hydrocarbon diluent to vaporize a substantial portion of said residual oil prior to contact with a siliceous catalyst in a first cracking zone under fluidized cracking conditions to effect a conversion of about 5 to about 20 percent such that a reaction product containing gas oil substantially free of carbon residue and metal contaminants is produced, separating a third gas oil fraction from the reaction product, combining the first, second and third gas oil fractions, said combined gas oil fractions having a carbon residue of not more than 0.6 percent and not more than 2 p.p.m. of metals, nickel equivalent, contacting the combined gas oil with a siliceous catalyst in a second fluidized cracking zone under suitable cracking conditions to effect a conversion of about 35 to about 75 percent such that a gasoline product of high anti-knock quality is produced.

11. A process for the production of gasoline which comprises treating a reduced crude in a separation zone for the production of a first gas oil fraction and a residual oil fraction, contacting the residual oil containing about 2.5 to 30 percent carbon residue, about 5 to 70 p.p.m. of metals, nickel equivalent, and substantially free of separable gas oil which is suitable for high level conversion of gasoline with the products of the second cracking step hereinafter described to vaporize a substantial portion of said residual oil prior to contact with a siliceous catalyst in a first fluidized cracking zone having an average $D+L$ activity of about 10 to 25 and under suitable fluidized cracking conditions to effect a conversion of about up to about 20 percent such that the catalyst is contaminated with carbonaceous material and a reaction product containing gas oil substantially free of carbon residue and metal contaminants is produced, subjecting the reaction product to treatment in a second separation zone whereby a gasoline product, a second gas oil fraction and a third fraction of liquid product boiling above the gas oil are produced, combining the said third fraction with the residual oil being charged to the first cracking zone, combining the first and second gas oil fractions and charging the same to a second fluidized cracking zone containing a siliceous catalyst having an average $D+L$ activity of about 20 to about 45 such that a reaction product containing gasoline of high anti-knock quality is produced, and combining the reaction product from the second cracking zone with the residual oil and the third fraction being charged to the first reaction zone.

12. A process for the production of gasoline which comprises contacting a residual oil containing at least about 1 percent by weight of carbon residue in the presence of a diluent to vaporize a substantial portion of said residual oil prior to contact with a fluidized cracking catalyst under cracking conditions in a first zone to effect not more than about 20 percent conversion to a reaction

product containing gas oil, separating the gas oil from the reaction product and passing the separated gas oil to a second zone wherein it is passed in contact with a cracking catalyst under fluidized cracking conditions to effect a conversion of at least about 35 percent to produce a second vaporous reaction product containing gasoline and combining the second vaporous product as the diluent for the residual oil passed to said first zone.

13. The process of claim 12 wherein the residual oil oil is a heavy residual oil having an API gravity of about 1° to about 12° and containing about 2.5 to about 30 percent by weight of carbon residue.

14. A process for the production of gasoline which comprises contacting a gas oil with a fluidized cracking catalyst in a first zone under fluidized cracking conditions to effect a conversion of at least about 35 percent, thereby producing a vaporous reaction product containing gasoline, gas oil, and product material heavier than gas oil, combining said vaporous reaction product at an elevated temperature with a residual oil to vaporize a substantial portion thereof and passing the same to a second zone in contact with a fluidized cracking catalyst under less severe cracking conditions to effect not more than about 20 percent conversion to produce a reaction product containing gasoline, gas oil and product material heavier and lighter than said gas oil, passing the total effluent from the second zone to a separation zone to recover a gas oil fraction and a heavier than gas oil fraction, passing the gas oil fraction from the separation zone to the first zone and passing the heavier than gas oil fraction from the separation zone to the second zone.

15. A process for the production of gasoline which comprises contacting a residual oil containing at least about 1 percent by weight of carbon residue and substantially free of separable gas oil suitable for high level conversion to gasoline in the presence of a diluent to vaporize a substantial portion of said residual oil prior to contact with a cracking catalyst in a first cracking zone under fluidized conditions to effect not more than about 20 percent conversion to a reaction product containing gas oil, separating a gas oil product from the first reaction product and passing the gas oil to a second zone wherein the gas oil is passed in contact with a cracking catalyst to produce a vaporous reaction product containing gasoline thereby contaminating the catalyst with carbonaceous material, withdrawing contaminated catalyst from the second zone and passing the contaminated catalyst to a regeneration zone wherein carbonaceous material is burned to produce a flue gas, withdrawing regenerated catalyst from the regeneration zone and pass-

ing separate portions thereof to the first and second cracking zones and employing a portion of the flue gas as the diluent for the residual oil passed to the first cracking zone.

5 16. A process for the production of gasoline which comprises contacting a residual oil containing at least about 1 percent by weight of carbon residue with a cracking catalyst in a first zone under fluidized cracking conditions to effect not more than about 20 percent conversion and thereby producing a reaction product containing gas oil, separating the gas oil from the reaction product and passing the gas oil to a second zone wherein it is contacted with a cracking catalyst to produce a second vaporous reaction product containing normally gaseous product material and gasoline and contaminating the catalyst with carbonaceous material, withdrawing the contaminated catalyst from the second zone and passing the contaminated catalyst to a regeneration zone wherein carbonaceous material is burned to produce flue gas, withdrawing regenerated catalyst from the regeneration zone and passing separate portions thereof to the first and second zones and combining with the residual oil prior to contact with catalyst with a diluent to vaporize a substantial portion of said residual oil selected from the group consisting of flue gas from the regeneration zone, the second vaporous reaction product and the normally gaseous product material.

10 17. The process of claim 16 wherein the residual oil is a heavy residual oil having an API gravity of about 1° to 12° and containing 2.5 to 30 percent by weight of carbon residue.
